UNITED STATES PATENT OFFICE.

WILLIAM K. GUNTER, OF GAFFNEY, SOUTH CAROLINA.

DESIGN FOR A BEDSPREAD OR SIMILAR ARTICLE.

Application filed October 22, 1926. Serial No. 19,444. Term of patent 14 years.

To all whom it may concern:

Be it known that I, WILLIAM K. GUNTER, a citizen of the United States, residing at Gaffney, in the county of Cherokee and State of South Carolina, have invented a new, original, and ornamental Design for a Bedspread or Similar Article, of which the following is a specification, reference being had to the accompanying drawings, forming part thereof.

The figure is a plan view of a bedspread illustrating the new design, the detailed showing in the lower portion of the drawing is continued throughout the size of the bed spread or similar article.

I claim:—

The ornamental design for a bedspread or similar article, as shown and described.

WILLIAM K. GUNTER.
